CLAIM

The ornamental design for a “graphic user interface for a medical monitor”, as shown and described.

DESCRIPTION

FIG. 1 is a top, front, right side perspective view of a graphical user interface for a medical monitor, the broken line drawing of a monitor is for illustrative purposes only and forms no part of the claimed design; and,

FIG. 2 is a front view of a second embodiment thereof, the broken line drawing of a monitor is for illustrative purposes only and forms no part of the claimed design.
